UNITED STATES PATENT OFFICE.

DAVID WALD, OF NEW YORK, N. Y.

RHEOSTAT CONSTRUCTION.

Application filed April 30, 1925. Serial No. 26,874.

This invention relates to new and useful improvements in rheostat construction, and more particularly to rheostatic devices designed to be employed in radio receiving apparatus.

5 One of the objects of the invention is to provide new and improved means for adjustably mounting a contact arm upon its operating shaft.

Another object of the invention is to provide new and improved mounting for the contact arm upon its shaft, whereby a nicer adjustment may be had than it has been possible to secure in devices of this character as hitherto constructed.

15 Another object of the invention is to provide means for clamping the operating arm to its shaft, whereby the latter will not be indented or otherwise mutilated by the clamping mechanism.

20 A still further object of the invention is to provide in a rheostat of the above type means whereby a relative adjustment between the contact arm and the operating knob of the rheostat may be readily effected.

25 Other objects and aims of the invention, more or less specific than those referred to above, will be in part obvious and in part pointed out in the course of the following description of the elements, combinations, arrangement of parts and application of principles, constituting the invention; and the scope of protection contemplated will be indicated in the appended claims.

30 In the accompanying drawings, wherein I have illustrated a preferred form of embodiment of my invention:

Figure 1 is an elevational view of a panel, showing my improved rheostat mounted thereon.

40 Figure 2 is a rear elevational view of my improved rheostat.

Figure 3 is a vertical sectional view taken substantially on the lines 3—3 of Figure 2.

45 Figure 4 is an elevational view of the contact arm; and

Figure 5 is a cross-sectional view taken through the rheostat showing a slightly modified form of construction.

50 Referring now to the drawings, wherein similar reference characters refer to similar parts throughout the several views thereof, the reference numeral 1 denotes a panel board of a radio set, upon which the rheostatic device is mounted. 2 indicates a circular block 55 of insulating material, which is adapted to be fastened to the panel 1 in any desired

manner, for instance as by means of clamping screws 3, which pass through the block and enter the panel. Block 2 carries the resistance unit 4, which is of the usual circular construction, so that the resistance wire may be engaged by the contact point 5 of the contact arm 6. One end of the resistance unit is connected with the binding post 7.

60 Extending through an aperture 8 in the block 2, and adapted to rotate therein, is a metallic sleeve 9, said sleeve being connected with the binding post 10 by means of the plate 11. This sleeve has a head 12, which passes through an aperture in said plate, so 65 that said sleeve is mechanically, as well as, electrically connected with the plate 11, and thereby with the binding post 10. Sleeve 9, at its outer end is threaded as at 13, and is provided with two flattened portions 14 and 70 15, the metal at these points being quite thin. 75 for a purpose which will be understood hereinafter.

75 The contact arm 6 is provided with an aperture 16, through which the outer threaded end of the sleeve 9 passes, the walls of the aperture having the straight portions 17 and 18, as shown, which are adapted to engage with the straight portions 14 and 15 respectively, of the sleeve, whereby said contact arm and said sleeve are non-rotatably connected.

80 Extending through the sleeve 9 is the operating shaft 19 of the device, said operating shaft being provided at its outer end with the operating knob or handle 20. Shaft 19 85 extends completely through the sleeve, as clearly shown in Figure 2. Threaded upon the outer end of the sleeve 9 is a nut 21, which nut, as will be seen, clamps the contact arm 6 against a circular shoulder 22 formed on the 90 insulating block 2, thereby holding the various movable parts of the device above described in assembled condition. The nut 21 is provided with a screw threaded laterally 95 extending aperture 23, through which extends the clamping screw 24.

100 The inner end of this clamping screw is adapted to engage with either of the flattened portions 14 or 15 of the sleeve 9, whereby the nut 21 is locked in this desired adjusted position upon the screw threaded end of said sleeve. The clamping screw 24, extending as it does through the nut 21, may be adjusted to distort the metal comprising either of the flattened portions 14 or 15 of the sleeve, whereby the sleeve will be caused tightly to engage with the operating shaft, so that the 110

associated parts will be locked or held frictionally against relative rotative movement.

At this point it may be noted that heretofore in the construction of rheostatic devices of this character it has been customary to employ a set screw which directly engages the operating shaft. Frequent adjustments of this set screw oftentimes indents or mutilates the shaft, so that it is quite difficult to obtain the fine adjustment of parts desirable in devices of this character. By means, however, of the construction just described, it will be seen that the distortion of the metal of the sleeve serves to frictionally clamp the parts together, there being no danger thereby of mutilating the shaft.

This construction has the further advantage that while the contact arm and its operating shaft 19 may be fastened together sufficiently firm for the usual operative purposes, such relative movement between the shaft and the contact arm can be had without loosening the clamping screw 24, as will permit initial adjustment, so that for instance the indicator arrow 25 can be caused to register exactly with the zero position of the device 26. This adjustment can be readily effected by forcing the shaft to rotative movement against the stress of the clamping means while the contact arm 6 is in engagement with either of the binding posts 7 or 10.

In Figure 5 of the drawings I have provided a slightly modified construction as to one feature of my invention. In this figure the clamping screw 24, it will be noted, passes through an aperture formed in one of the flattened faces 14 or 15 of the sleeve 9, and directly engages with the operating shaft 19. In this modification the clamping screw 24 locks the operative parts together through direct engagement with the shaft, and also prevents a retrograde movement of the nut 21 upon the threaded portion 13 of the sleeve 9.

It will accordingly be seen that I have provided a construction well adapted to attain, among others, all the ends and objects above pointed out, in a very simple manner. The device is readily assembled, is not easily distorted, and provides for a very accurate adjustment of parts.

As many changes could be made in this construction without departing from the scope of the following claims, it is intended that all matter contained in the above description or shown in the accompanying drawings, shall be interpreted as illustrative only and not in a limiting sense.

Having thus described my invention what I claim as new and desire to secure by Letters Patent is:—

1. A device of the class described, in combination, a resistance unit, a contact arm adapted to be moved thereover, a mounting

for said resistance unit, a mounting for said contact arm, comprising a sleeve with which said contact arm is non-rotatably engaged, a shaft extending through said sleeve, and provided with an operating knob or handle, a nut threaded upon said sleeve, and means extending through said nut, and engaging said sleeve, adapted to distort the material thereof, so that said sleeve and said shaft are operatively connected. 65

2. In a device of the class described, in combination, a block of insulating material, a resistance unit carried thereby, a contact arm having a contact point adapted to traverse said resistance unit, a sleeve extending through said block, said sleeve being threaded at its outer end and provided with one or more flattened surfaces adjacent the screw threaded part thereof, said contact arm being mounted upon said sleeve in non-rotatable relation therewith, a nut threaded upon said sleeve, and a clamping screw extending through said nut, adapted to engage a flattened portion thereof, and cause the latter to impinge against said shaft, so that said sleeve and said shaft are held frictionally in operative relation. 80

3. In a device of the class described, in combination, a block of insulating material, a resistance unit carried thereby, the contact arm having a contact point adapted to traverse said resistance unit, a sleeve extending through said block, said sleeve at its outer end being provided with a threaded portion and with one or more flat faces, said contact arm being mounted upon said sleeve in non-rotatable relation therewith, a shaft provided with an operating handle extending through said sleeve, a nut threaded upon said sleeve, adapted to clamp and hold said contact arm in position thereon, and a clamping screw extending through said nut, adapted to engage a flat face on the sleeve, whereby said sleeve and said shaft are clamped in operative position. 95

4. In a device of the class described, in combination, a block of insulating material, a resistance unit carried thereby, a sleeve extending through said block, a pair of binding posts, one of which is connected with the resistance unit, and the other with said sleeve, said sleeve at its outer end being provided with a screw threaded part, and with one or more flat faces, a contact arm mounted upon said sleeve and having a contact point adapted to traverse said resistance unit, a shaft extending through said sleeve, and being provided with an operating knob or handle, a nut threaded upon said sleeve, and means extending through said nut adapted to hold said sleeve and said shaft in operative relation. 100

In testimony whereof, I affix my signature.
DAVID WALD.
